UNITED STATES PATENT OFFICE

JEAN DOGNIN, OF PARIS, FRANCE, ASSIGNOR TO THE LACE NET IMPORTING CO. INC.,
OF NEW YORK, N. Y.

DESIGN FOR LACE

Application filed July 15, 1932. Serial No. 44,350. Term of patent 3½ years.

To all whom it may concern:

Be it known that I, JEAN DOGNIN, a citizen of France, residing in Paris, in the Republic of France, have invented a new, original, and ornamental Design for Lace, of which the following is a specification, reference being had to the accompanying drawing, forming part thereof.

The drawing shows a face view of a piece of lace embodying my design.

It is contemplated that the demarcated areas of the design, that are not cross hatched, may be of any desired contrasting colors.

I claim:

The ornamental design for lace, substantially as shown and described.

JEAN DOGNIN.
